(57) **CLAIM**

I claim the ornamental design for an input/output module, as shown and described.

DESCRIPTION

FIG. 1 is a front perspective view of an input/output module, showing my new design:

FIG. 2 is a front elevational view of the input/output module of FIG. 1;

FIG. 3 is a rear elevational view of the input/output module of FIG. 1;

FIG. 4 is a left side elevational view of the input/output module of FIG. 1;

FIG. 5 is a right side elevational view of the input/output module of FIG. 1;

FIG. 6 is a top plan view of the input/output module of FIG. 1; and,

FIG. 7 is a bottom plan view of the input/output module of FIG. 1.

The broken line showing in the figure drawings is included for illustrative purposes only and forms no part of the claimed design.
